UNITED STATES PATENT OFFICE.

JOHN A. OFFNER, OF BALTIMORE, MARYLAND, ASSIGNOR OF ONE-FOURTH
TO ALEXANDER J. ABRAMS, OF SAME PLACE.

SUPPORT FOR FIRE-HOSE.

SPECIFICATION forming part of Letters Patent No. 443,460, dated December 23, 1890.

Application filed August 13, 1890. Serial No. 361,891. (No model.)

To all whom it may concern:

Be it known that I, JOHN A. OFFNER, a citizen of the United States, residing at Baltimore, in the State of Maryland, have invented 5 certain new and useful Improvements in Supports for Fire-Hose, of which the following is a specification.

This invention relates to a device for supporting fire-hose at an elevated position above 10 the tracks of street-cars in order to avoid obstructing the passage of the cars in time of fire.

The invention is illustrated in the accompanying drawings, in which—

15 Figure 1 is a view of the device, showing a portion of fire-hose raised above the top of the cars of a double-track road. Fig. 2 shows a view of one of the derricks and the means whereby the hose is elevated. Fig. 3 shows 20 a cross-section of the hose, the trough, and the suspending-hook. Fig. 4 is a sectional view of the top portion of one of the derricks, showing the pulley-block thereof.

The letter A designates the fire-hose, which 25 is carried over the tops of the cars B, which run on a street-railway track; C, the three posts of the derrick, which have points n at their lower ends in order to prevent slipping, and the upper ends are joined together by a 30 pivot-bolt a. Two of these derricks are used, one on either side of the track. The pivot-bolt a passes loosely through the posts C of the derrick and has suitable means a' to prevent it from slipping through the posts. A 35 pulley block or hanger d has a pulley d', and is supported by the bolt a. The two sides of the hanger take on either side of the center post C and between it and the two side posts. Thereby the pulley d' hangs in the center of 40 the three posts. Over the pulley d' passes the rope e for raising or lowering the hose. At one end of this rope is a suspension-hook f, and at the other is a hook or ring g to take over a hook or pin h on one of the derrick 45 posts when it is desired to support the fire-hose.

A hose-trough D is semicircular in cross-

section, and has attached on either side, at a point distant from the end equal to one-third the length of the trough, a hinged plate i, 50 which has at its free end a hole j, through which passes the suspending hook f, attached to the rope e. The short portion of the trough, or the one-third length k, extends toward or over the railway-track, and in use this end is 55 also raised higher than the long end l. (See Figs. 1 and 2.)

A derrick equipped as described above is placed on either side of the car-track, and the hose A placed in the trough D, the hinges of which are then brought together and the hook f inserted into the holes j thereof, after which the trough is raised by the rope e and the pulley d', over which the rope passes.

As the long end l of the hose-troughs is 65 placed outward, the weight of the hose resting thereon will be greater than at the short end k. Consequently the troughs, when in use, will assume an inclined position, as shown, 70 with their elevated ends confronting each other and supporting the hose between them. It will now be seen that the hose on the two troughs will form an arch m over the tracks.

It is obvious that the troughs may be made to receive one, two, three, or more lines of 75 hose and support them, as described.

A fire-hose support of this kind is especially applicable for street-car lines where the endless cable is the means of propulsion.

Having described my invention, I claim— 80

1. In combination with a derrick having a pulley-block and rope, a hose-supporting trough having but one pair of suspension-plates i, which are attached nearer to one end than to the other, whereby when in use the trough will assume an inclined position. 85

2. The combination of a pair of derricks, a pulley-block suspended from the top of each derrick, and a separate hose-supporting trough for each derrick, each suspended by a single rope passing over the pulley-block and connected to the trough at a point nearer one end than the other, whereby when in use 90 each trough may assume an inclined position

with its elevated ends confronting each other and supporting the hose between them, as set forth.

3. In combination with a derrick having a pulley-block and rope, a hose-supporting trough having a single pair of plates, one hinged to each side and adapted to be brought together over the hose, where a hook on the

end of the said rope will take through both of them.

In testimony whereof I affix my signature in the presence of two witnesses.

JOHN A. OFFNER.
